UNITED STATES PATENT OFFICE.

HERMAN C. MAISE, OF DETROIT, MICHIGAN, ASSIGNOR TO BRIGGS MANUFACTURING COMPANY, OF DETROIT, MICHIGAN, A CORPORATION OF MICHIGAN.

WINDOW FRAME.

Application filed August 27, 1923. Serial No. 659,671.

This invention relates to frames and refers more particularly to window frames designed for receiving vertically movable sashless glass panels.

5 An object of the invention is to provide a strong and durable frame and anti-rattling means therefor which may be readily assembled on a suitable work bench and which as a unit may be easily and quickly mounted in or removed from a window 10 opening in a suitable support.

Another object is to provide a frame in which the glass panel is preferably guided by flexible channel members preferably 15 having portions that extend freely downwardly below the frame and that are preferably connected to the anti-rattling means whereby the latter will hold the free portions of the channels to facilitate the movement of the panel therein.

Another object is to provide a two part frame and a common connection between the parts of the frame and the anti-rattling means therefor.

25 With the above and other objects in view, the invention consists of certain novel features of construction, combination and arrangement of parts as will be more fully described and particularly pointed out in 30 the appended claims.

In the accompanying drawings:

Figure 1 is a side elevation of a vehicle door and showing the frame embodying my invention applied thereto;

35 Figure 2 is a vertical sectional view taken on line 2—2 of Figure 1;

Figure 3 is a fragmentary sectional view taken on line 3—3 of Figure 2;

Figure 4 is a fragmentary sectional view 40 taken on line 4—4 of Figure 2;

Figure 5 is a detail perspective view of one of the springs.

Referring now to the drawing in which like characters of reference designate corresponding parts throughout the several views, the numeral 1 designates a sashless glass panel that is adapted to be raised or lowered in a door 2, preferably of a vehicle body. In the upper portion of the door is a window opening 3 that is adapted to be closed by the glass panel when in raised position, while in the lower portion of the door is a vertical pocket 4 that communicates with the opening 3 and that is adapted 50 to receive the glass panel when in lowered

position. Any suitable mechanism (not shown) may be used for raising and lowering the glass panel in the door.

For receiving the panel when it is raised, I preferably provide a frame 5 that is 60 preferably detachably mounted in the window opening 3. This frame may be constructed of any suitable material but is preferably formed of two strips of metal 6 and 7 respectively. The strip 6 preferably comprises a channel portion 8 and a transversely curved portion 9, the latter preferably extending laterally from one side of the channel portion 8 and being preferably provided at its outer edge with a 70 return-bent flange 10 that is in alignment with the base 11 of the channel. The strip is preferably of sufficient length to extend around the upper and side walls of the window opening and, to provide a snug fit at 75 the corners. The strip is preferably provided at spaced points with transversely extending substantially V-shaped notches 12 which will permit the strip to be readily bent so as to provide a horizontal header section 13 and parallel vertical side sections 14 for engagement respectively with the upper and side walls of the window opening.

The strip 7 cooperates with the strip 6 to form the frame 5 and for this purpose 85 is preferably secured at its opposite ends by bolts 15 to a pair of horizontal flanges 16 extending inwardly from the lower free ends of the vertical sections 14 of the strip 6. The strip 7 is preferably provided at its 90 outer edge with a downwardly extending return-bent flange 17, while at its inner edge it is preferably provided with a straight depending flange 18 that preferably engages the inner sides of the vertical 95 channel portions of the strip 6, the body portion of the strip 7 being preferably curved transversely as shown at 19 and serves as a suitable belt finish strip for the door.

For guiding the panel 1 vertically in the frame 5, I preferably provide strips of channel felt 20 that receive the opposite side edges of the panel and that are preferably secured in the channel portions of the vertical side sections 14 of the frame. The channel portion of the header section 13 is adapted to receive the upper edge of the panel when it is in raised position while portions 21 of the felt channels 20 prefer-

100

105

110

ably extend downwardly a sufficient distance into the pocket 4 for guiding the panel therein when it is lowered below the belt strip 7.

5 When the frame 5 is positioned in the window opening 3 the inner side 22 of the channel portion of the header section 13 preferably abuts a depending projection 23 of the upper cross bar 24 of the door frame 10 while the bases of the channels and the return-bent flanges 10 of each section of the strip 6 preferably have an extended bearing upon the upper and side walls respectively of the window opening. For 15 holding the frame in position, the header section 13 is preferably provided with spaced openings 25 through which screws 26 or other suitable securing elements may be driven into the upper cross bar 24 of 20 the door frame. These screws preferably form the sole means of attachment of the frame to the door, thus the frame may be easily and quickly positioned in or removed from the window opening 3.

25 In the past it was a common occurrence for the fastening means for window frames to become loosened, allowing the frames to rattle and cause undue noise. In the present instance, in case the bolts 15 gradually loosen 30 up and allow the frame 5 to rattle, I have provided means associated therewith for taking up the play, said means at all times being adapted to bear against the inside lower portion of the frame 5 forcing the 35 same against a portion of the door frame and thereby preventing rattling of the window frame 5. For accomplishing this, I preferably provide a pair of bowed springs 27 that engage an inwardly extending flange 40 28 at the upper edge of the usual lock toward 29 forming a part of the door frame and that yieldably hold the frame 5 against the depending projection 23 and the lateral projections 30 upon the standards 31 of the door 45 frame. These springs are preferably provided at their upper ends with horizontal flanges 32 that are preferably secured to the strip flanges 16 by means of the bolts 15, and are preferably provided at their lower ends 50 with straight depending portions 33 that are preferably in alignment with the depending flange 18 at the inner edge of the belt strip 7.

For holding the downward extensions 21 of the channel guides in alignment with the 55 fixed portions 20 thereof within the frame, I preferably secure the bases of the downwardly extending portions 21 of the channels to lugs 34 extending laterally from one edge of the straight portions 33 of the springs 27.

60 For reinforcing the connection between the belt strip 7 and the flanges 16 and 32 respectively of the strip 6 and springs 27, I preferably provide a horizontal angle bar 35 that is preferably held against the flanges 32 of the springs by means of the same bolts

15 that secure the belt strip 7 to the flanges 16 of the strip 6. In view of the fact the bolts 15 secure the springs, angle member and frame together, these parts together with the channel guides and glass panel may 70 be readily assembled by one person upon a suitable bench and subsequently applied to the door as a unit. For example, after the parts referred to have been assembled the frame 5 may be inserted into the window 75 opening 3 of the door in such a manner that the free lower ends of the springs 27 will move into the pocket 4 and the bowed portions of the springs will engage the inwardly extending flange 28 at the upper edge of the 80 lock board 29. The screws 26 may then be driven through the openings in the header section 13 of the frame and into the upper cross bar 24 of the door frame for detachably holding the frame in position. Thus, 85 it is apparent that the time and labor required for assembling the various parts and attaching the same to a door is reduced to a minimum.

90 While it is believed that from the foregoing description the nature and advantages of the invention will be readily apparent, I desire to have it understood that I do not limit myself to what is herein shown and described and that such changes may be 95 resorted to when desired as fall within the scope of what is claimed.

What I claim as my invention is:—

1. The combination with a support having an opening therein, of a two-part frame 100 removably mounted in said opening, anti-rattling means for said frame projecting from said frame and engaging said support and a common connection between the parts of said frame and said anti-rattling means. 105

2. The combination with a support having a window opening, and a transparent panel movable in the support to close the opening, of a frame adapted to be mounted in the opening to receive the panel, means securing the frame to the support in substantial registration with said opening and means secured to said frame and adapted to engage said support for preventing said frame from rattling. 110

115 3. The combination with a support having a window opening therein and a pocket communicating with the opening, of a frame in the opening, flexible channel members secured to said frame and having portions extending freely into said pocket, a transparent panel adapted to travel in the channels of said members, anti-rattle means for said frame including yieldable members projecting from the frame, and means for securing the extensions of said channel members to said yieldable members adjacent to the free ends thereof, means whereby the latter will hold the free portions of the channels to facilitate movement of the panel therein. 120 125 130

4. The combination with a support having a window opening therein and a pocket communicating with said opening, a frame secured to said support in substantial registration with said opening, channel members secured to said frame and having portions projecting freely into said pocket, a closure for said opening slidable in said channel members, and anti-rattle means secured within said pocket to said channel members.

5. The combination with a support having a window opening therein and a pocket communicating with said opening, a frame secured to said support in substantial registration with said opening, a pair of guide members extending within said pocket, a closure for said opening slidable in said guide members and frame, and a spring terminally secured to said frame and to one of said guide members and bearing freely upon said support within said pocket.

6. The combination with a support having a window opening therein and a pocket communicating with said opening, a frame removably mounted in said opening, means securing said frame to the support in substantial registration with said opening, channeled guide members secured to the frame and extending into said pocket and forming with the frame a removable unit, and a closure for said opening slidable in said guide members and frame.

7. In a vehicle body, the combination with a window frame, a sliding window movable in said frame, and flexible runways for said window projecting below the frame, of means for yieldably holding the projecting portions of said runways in position to receive the window including a spring metal strip secured to said frame and runways.

8. In combination, a door having a window opening and inwardly extending lateral projections at the top and side edges of said opening, a glass panel movable longitudinally of said door to close said opening, a removable frame in said opening having means for receiving said glass panel when in closed position, and yieldable means carried by said frame and engaging a portion of said door for maintaining said frame against said lateral projection.

9. In combination, a door having a window opening, and inwardly extending lateral projections at certain edges of said opening, a glass panel movable longitudinally of said

door to close said opening, a removable frame in said opening, guide strips for said glass panel carried by said frame and projecting downwardly below the window opening, and yieldable means carried by said frame and engaging a portion of said door for maintaining said frame against said lateral projections, said yieldable means being secured to said guide strips below said window opening and holding the latter in position to receive said glass panel when lowered below said window opening.

10. In combination, a door having a window opening, and an inturned lateral flange below said opening, a removable window frame in said window opening, and a yieldable element carried by said frame and engaging said inturned lateral flange so as to maintain said window frame in a predetermined position in said opening.

11. In combination, a door having a window opening, an inwardly extending lateral projection at an edge of said opening, and an inwardly extending lateral flange below said window opening, a removable window frame in said opening, and a yieldable element carried by said frame and engaging said lateral flange for maintaining said frame against said lateral projection.

12. In combination, a window frame, window guide strips having portions secured to the sides of said frame and having other portions projecting below the lower portion of said frame, and laterally spaced yieldable elements projecting from the lower portion of said frame and extending longitudinally of said guide strips, and projections on said yieldable elements secured to said depending portions of said guide strips and holding the latter in substantial alignment with the first mentioned portions of said guide strips.

13. In combination, a frame having the top and sides thereof formed from one piece of metal, and having a separate sill member, the sides of said frame having inturned flanges secured to said sill member at the ends thereof, a reinforcing bar for said frame secured to said inturned flanges, window guides having portions secured to the sides of the frame and having other portions projecting below the sill member, and yieldable elements secured to said window guides and having flanges secured to said sill member and reinforcing bar.

In testimony whereof I affix my signature.
